(57) CLAIM

The ornamental design for a license plate frame box, as shown and described.

DESCRIPTION

FIG. 1 is a perspective view of a license plate frame box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the license plate frame box where a box cover is coved on a main box body;

FIG. 10 is an enlarged view of portion 10 shown in FIG. 7; and,

FIG. 11 is an enlarged view of portion 11 shown in FIG. 8. The broken lines in the drawings depict portions of the license plate frame box that form no part of the claimed design.
